THERMOSTATIC CONTROL FOR STOVE AND RANGE OIL BURNERS

Henry Keebler, Secaucus, N. J.

Application May 15, 1940, Serial No. 335,373

3 Claims. (Cl. 236—99)

This invention relates to thermostatic control for stove and range oil burners.

An object of this invention is to provide a thermostatic control of the character described provided with highly improved means for regulating the temperature desired in the room.

Yet another object of this invention is to provide a compact and durable thermostatic control of the character described, which shall be relatively inexpensive to manufacture, easy to regulate, which shall be smooth and positive in operation, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

The single figure of the drawing is a side elevational view of a thermostatic control embodying the invention, in conjunction with a stove, and with parts in cross-section.

Referring now in detail to the drawing, 10 designates a stove or range, and 11 designates a thermostatic control for the fuel for the burners for the stove or range 10.

The thermostatic control 11 comprises a vertical pipe 12, to the lower end of which is screwed a valve housing chamber 13. The chamber 13 has a bottom wall 14, formed with an opening 15 closed by a screw plug 16. Said chamber 13, furthermore, has opposite walls 17 and 18, and a transverse partition 19 interconnecting said walls, and formed with a central valve opening 20.

Attached to wall 17, below the partition 19, is a pipe 21 connected to a fuel tank; and connected to the opposite wall 18, and above the partition 19, is a pipe 22 leading to the burners for the stove or range 10.

Extending through the pipe 12 is a vertical rod 25 formed with a valve head 26 at its lower end adapted to close the valve opening 20. Interposed between the valve head 26 and the plug 16, is a coil compression spring 27 to normally raise the rod 25 for opening the valve and permit passage of fuel from pipe 20 to the pipe 22.

Means is provided to regulate the position of the rod 25. To this end, there is fixed to the upper end of the pipe 12, a bracket 30 having an

opposite arm 31 extending to one side of the pipe 12. Extending from the arm 31 is a horizontal arm 32 overlying the upper end of the pipe 12, and extending from the arm 32, are a pair of upwardly extending arms 33 and 34, for the purpose hereinafter appearing.

Arm 32 is formed with an internal screw threaded opening 36 aligned with the pipe 12. Screwed within said opening is a screw threaded member 37 formed with a slot 38 at its lower end. Fixed to the upper end of the rod 25 is a head 48 having a transverse flange 41 received within the slot 38.

The screw threaded member 37 is formed with an axial smooth opening 43 extending down to the slot 38. At the upper end of the screw threaded member 37 is a large head 45 which may be turned to adjust the position of said screw threaded member. Slidably mounted in the opening 43 is a pin 46. To the upper end of the pin 46 is a head 48. The lower end of the pin 46 contacts the upper end of portion 41 of the rod 25. Pivoted to the arm 34 is a lever 50 having one arm 51 contacting the upper side of the head 48.

Fixed to the bracket 30 is an angular arm 52 having a horizontal portion 53 and a vertical upwardly extending portion 54. Fixed to the upper end of the arm 52 is a thermostatic unit 55 of the disc type.

When the thermostatic unit 55 heats, the top of the disc expands and moves upwardly. The second arm 56 of lever 50 contacts the upper side of the thermostatic unit 55.

It will now be understood that as the heat from the range increases, the thermostatic unit 55 will expand and move upwardly to rotate the lever 50 in a counter-clockwise direction, to press down on the rod 25 to cut down on the fuel. When the heat decreases, the spring 27 turns the rod 25 upwardly to increase the valve opening.

Thus, the thermostatic control 11 regulates the burner flames.

Means is provided to regulate the thermostatic control unit. To this end, there is fixed to the arm 33, a horizontal arm 60. Pivoted to the arm 60, as at 61, is a curved bracket 62. Pivoted to the outer end of the bracket 62 is a canopy 63 overlying the thermostatic unit. The vertical position of the canopy may be adjusted by swinging the bracket 62 up or down as desired.

It will now be understood that the position of the canopy 63, relative to the thermostatic unit 55, will control the effectiveness of said unit.

Thus, as the canopy is moved down, the thermostatic unit will be heated more quickly and vice versa.

The position of the canopy 63 may be determined by means of a bracket 65 fixed to the bracket 52 and having a vertical portion 66 marked with graduations 67. The vertical arm 66 is positioned alongside of the canopy to facilitate determination of the position of the canopy.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A thermostatic control of the character described comprising a valve chamber, a pipe fixed thereto, a rod mounted within said pipe for longitudinal sliding movement, a valve head at the lower end of the rod disposed within said valve chamber, said rod projecting above said pipe, a bracket on said pipe formed with a screw threaded opening coaxial with said rod, a screw threaded member within said opening formed with a slot at its lower end, a member fixed at the upper end of the rod provided with a portion received within said slot, whereby rotation of said screw threaded member will cause rotation of said rod about its axis, and whereby said rod can move axially of said member, said screw threaded member being formed with an axial opening communicating with said slot, a pin within said opening, a head at the upper end of said pin, a lever pivoted to said bracket having one arm engaging the head on said pin, and a thermostatic unit supported on said bracket, the other arm of said lever engaging said thermostatic unit.

2. A thermostatic control of the character described comprising a valve chamber, a pipe fixed thereto, a rod mounted within said pipe for longitudinal sliding movement, a valve head at the

lower end of the rod disposed within said valve chamber, said rod projecting above said pipe, a bracket on said pipe formed with a screw threaded opening coaxial with said rod, a screw threaded member within said opening formed with a slot at its lower end, a member fixed at the upper end of the rod provided with a portion received within said slot, whereby rotation of said screw threaded member will cause rotation of said rod about its axis, and whereby said rod can move axially of said member, said screw threaded member being formed with an axial opening communicating with said slot, a pin within said opening, a head at the upper end of said pin, a lever pivoted to said bracket having one arm engaging the head on said pin, a thermostatic unit supported on said bracket, the other arm of said lever engaging said thermostatic unit, an arm pivoted to said bracket, and a canopy pivoted to said arm and overlying said thermostatic unit, and adjustable toward and away from said thermostatic unit.

3. A thermostatic control of the character described comprising a valve chamber, a pipe fixed thereto, a rod mounted within said pipe for longitudinal sliding movement, a valve head at the lower end of the rod disposed within said valve chamber, said rod projecting above said pipe, a bracket on said pipe formed with a screw threaded opening, a screw threaded member within said opening formed with a slot at its lower end, a member at the upper end of the rod provided with a portion received within said slot, said screw threaded member being formed with an axial opening communicating with said slot, a pin within said opening, a head at the upper end of said pin, a lever pivoted to said bracket having one arm engaging the head on said pin, a thermostatic unit supported on said bracket, the other arm of said lever engaging said thermostatic unit, an arm pivoted to said bracket, a canopy pivoted to said arm and overlying said thermostatic unit and adjustable toward and away therefrom, and a member fixed to said bracket and having a vertical arm disposed adjacent the rim of said canopy and marked with graduations.

HENRY KEEBLER.
